CASING HEAD

Laurence L. Rector, Fort Worth, Tex.

Application July 19, 1937, Serial No. 154,411

5 Claims. (Cl. 166—14)

This invention relates to new and useful improvements in casing heads.

One object of the invention is to provide an improved casing head adapted to be secured to a well casing or other support and having means for supporting and packing off around a string of pipe or well tubing.

An important object of the invention is to provide an improved casing head which is constructed of a minimum number of parts, whereby manufacturing costs are reduced to a minimum; said device being readily assembled or disassembled which facilitates handling thereof.

Another object of the invention is to provide an improved casing head formed of a tubular section of pipe having a collar screwed to its upper end, whereby the upper end of the pipe provides a support for the well tubing and the collar forms a packing chamber wherein packing may encircle the tubing above the support to pack off therearound.

Still another object of the invention is to provide an improved casing head wherein the tubing is supported on a split ring, there being a removable member mounted on the upper end of the head, which member not only forms a packing chamber but also acts to prevent upward displacement of the supporting ring; the member being so mounted that it may be removed without disturbing the ring or tubing.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a view, partly in elevation and partly in section, of a casing head, constructed in accordance with the invention, and

Figure 2 is a horizontal, cross-sectional view, taken on the line 2—2 of Figure 1.

In the drawing, the numeral 10 designates a tubular body, which may be a section of pipe. The body is externally screw-threaded at its upper end as shown at 11, while similar external screw-threads 14' are provided at the lower end thereof, whereby said body may be screwed into the upper end of a well casing A or other support. The body 10 could, if desired, be an ordinary tubular connecting nipple such as is employed for connecting two sections of a well casing or other pipe. Openings 12, which are located diametrically opposite each other, are

drilled or formed in the wall of the body 10 at substantially mid-height thereof and each opening is surrounded by an internally screw-threaded collar 13 which is secured to the body by welding or otherwise. Obviously the collars 13 project radially from the outer surface of the body 10 and suitable outlet pipes 15 may be threaded into the collars 13 to connect said pipe to the body. With such arrangement, it will be obvious that the well fluid flowing upwardly through the casing A may enter the lower end of the body 10 and pass outwardly through the openings 12 and pipes 15. Manifestly, the openings 12 provide the usual outlet ports which are formed in the casing heads now on the open market.

For supporting the well tubing B which extends axially through the well casing A, a split ring 16 is provided with an annular shoulder 17 at its marginal portion on the underside thereof. This shoulder is arranged to seat on the upper edge of the body 10, as is clearly shown in Figure 1 and it is preferable that the ring 16 be split so as to facilitate its insertion, as will be explained. The inner surface of the ring is provided or formed with a recess 18 at its top and a fiber ring 19 is inserted in this recess. Although it is preferable to make the ring 19 of fiber, it may be made of any elastic material. The well tubing B extends downwardly through the split ring 16, there being only a slight clearance between the exterior surface of the tubing and said ring, whereby the coupling C connected in the tubing string cannot pass through the ring. Therefore when the tubing B is lowered to a point where the lower edge of its coupling C strikes the upper end of the ring 16, it will be evident that the tubing will be suspended from the ring. The lower edge of the coupling collar C not only engages the top of the split metallic ring 16, but also engages the ring 19 which is of a flexible material and therefore a seal between the lower edge of the coupling collar and its support is obtained.

For packing off around the coupling collar C which is supported on the split ring 16 a collar or extension collar 20 has the lower end of its bore internally screw-threaded so as to be mounted on the upper end of the body 10. The upper end of the collar is flared outwardly as is clearly shown in Figure 1, so that it is thicker at its upper end. An inwardly projecting annular flange 21 is preferably formed integral with the bore of the collar 20 and when said collar is threaded onto the upper end of the body 10, this

flange overhangs the split ring 16 so as to prevent upward displacement of said ring. The top of the inwardly projecting flange 21 also forms the bottom of a packing chamber 22, wherein an elastic packing element 23 which is made of rubber, rubber compound or other similar material, is mounted. By observing Figure 1, it will be evident that the packing member or element 23 is confined between the bore of the collar 20 and the outer surface of the coupling collar C. For deforming the packing element 23 into sealing engagement with the surface of the collar C, a flanged packing gland 24 has its lower end engaging the top of the member 23. Stud bolts 25 pass through the flange of the gland 24 and are threaded into openings 26 provided in the top of the collar 20. Manifestly, when the bolts 25 are tightened, the gland 24 is moved downwardly to deform the packing member 23 into sealing engagement with the surface of the collar C, whereby pressure within the casing A and body 10 cannot escape upwardly past the collar C.

From the above, it will be seen that a very simple and effective casing head is formed. A minimum number of parts are employed and due to the construction of these parts, manufacturing costs are reduced to a minimum. The body 10 may be made of an ordinary connecting nipple which has the openings 12 drilled in its wall. The collars 13 which surround the openings 12 are readily attached to the body by welding or otherwise.

The collar 20 may be removed from the body 10 while the tubing B is supported by the split ring 16, whereby the packing element 23 may be replaced without disturbing the tubing support. When it is desired to remove the split ring 16, it is only necessary to unscrew the collar 20 and raise the tubing B so that the lower edge of the collar C is lifted off of the ring 16. The ring may then be readily removed and the tubing run downwardly through the well casing. If it is desired to support the tubing by the coupling next above the collar C which is shown in the drawing, the split ring may be just as easily replaced to rest on the upper end of the body 10 whenever desired. The simplicity of the device not only reduces the manufacturing costs to a minimum but facilitates handling of the device in actual operation.

What I claim and desire to secure by Letters Patent is:

1. A casing head including, a tubular body adapted to be mounted on a well casing and having a well tubing extending therethrough, removable means resting on the upper end of the body for supporting the tubing within the body and casing, a collar mounted on the upper end of the body and extending upwardly above the tubing supporting means, an internal flange within the bore of the collar immediately overhanging and confining said supporting means to prevent upward displacement thereof, a packing element within the bore of the collar resting on the flange and surrounding the tubing for packing off around said tubing, and means attached to the collar for deforming the packing element into sealing engagement with the tubing.

2. A casing head including, a tubular body adapted to be mounted on a well casing and

having a well tubing extending therethrough a split metallic ring resting on the upper end of the body and adapted to be engaged by the lower edge of one of the coupling collars of the well tubing whereby said tubing is suspended from the ring, a collar mounted on the upper end of the body and extending upwardly above the ring, an inwardly directed flange within the bore of the body overlying the ring to confine the same and prevent upward displacement thereof, and a packing element within the collar supported on the flange and surrounding the tubing for packing off around said tubing.

3. A casing head including, a tubular body adapted to be mounted on a well casing and having a well tubing extending therethrough a split metallic ring resting on the upper end of the body and adapted to be engaged by the lower edge of one of the coupling collars of the well tubing whereby said tubing is suspended from the ring, a collar mounted on the upper end of the body and extending upwardly above the ring, an inwardly directed flange within the bore of the body overlying the ring to confine the same and prevent upward displacement thereof, a packing element within the collar supported on the flange and surrounding the tubing for packing off around said tubing, and a flanged packing gland carried by the collar and engaging the element for packing off around the tubing.

4. A casing head including, a tubular body adapted to be mounted on a well casing and having a well tubing extending therethrough, a split metallic ring resting on the upper end of the body and adapted to be engaged by the lower edge of one of the tubing coupling collars, whereby said tubing is suspended from the ring, said body having a radial outlet port therethrough for connection with an outlet pipe, a collar threaded on the upper end of the body and extending upwardly above the ring, an inwardly directed flange within the bore of the collar overlying the ring to confine the same and prevent upward displacement thereof, and a packing element within the collar supported on the flange and surrounding the tubing for packing off around said tubing.

5. A casing head comprising a body member having outlet conductor connecting means and adapted to be mounted on a well casing and having a well tubing extending therethrough, a coupling collar connecting sections of the well tubing, a supporting and packing member resting on the body member and engaging the lower end of said well tube coupling collar to support and seal the same, an extension collar removably secured to the upper portion of said body member and encasing said supporting and packing member, an internal flange within said extension collar adapted to immediately overhand said supporting and packing member when the extension collar is secured in position on the body member and thereby prevent upward displacement of the supporting and packing member, a second supporting and sealing means secured within the upper portion of the extension collar against the upper side of the internal flange thereof and also in sealing engagement with the well tube coupling collar.

LAURENCE L. RECTOR.

CERTIFICATE OF CORRECTION.

Patent No. 2,159,401.

May 23, 1939.

LAURENCE L. RECTOR.

It is hereby certified that error appears in the printed specification of the above numbered patent requiring correction as follows: Page 2, second column, line 60, claim 5, for "overhand" read overhang; and that the said Letters Patent should be read with this correction therein that the same may conform to the record of the case in the Patent Office.

Signed and sealed this 22nd day of August, A. D. 1939.

Leslie Frazer
